Primary Examiner — Deanna L Pratt(74) *Attorney, Agent, or Firm* — Cantor Colburn LLP(57) **CLAIM**

We claim, the ornamental design for a tool, as shown and described.

DESCRIPTION

FIG. 1 is a perspective view of an embodiment of the invention;

FIG. 2 is a top view of the embodiment of FIG. 1;

FIG. 3 is a bottom view of the embodiment of FIG. 1;

FIG. 4 is a first end view of the embodiment of FIG. 1;

FIG. 5 is a second end view of the embodiment of FIG. 1;

FIG. 6 is a first side view of the embodiment of FIG. 1; and,

FIG. 7 is a second side view of the embodiment of FIG. 1.

The phantom lines shown in FIG. 1-FIG. 7 illustrate portions of tool that form no part of the claimed design.
